Primary Examiner — T Chase Nelson*Assistant Examiner* — Rachel Wolfe(74) *Attorney, Agent, or Firm* — Charles C. Achkar; Ostrolenk Faber LLP.(57) **CLAIM**

The ornamental design for a screen bar lamp, as shown and described.

DESCRIPTION

FIG. 1 is a front elevational view of my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a bottom, right perspective view thereof; and,

FIG. 8 is a top, left perspective view thereof.

1 Claim, 8 Drawing Sheets(56)
